GARMENT HANGER

Mary J. Wilhelm, 7926 N. Gloucester, Portland, Oreg.

Filed June 12, 1962, Ser. No. 70,511

Term of patent 14 years

(Cl. D80—8)

FIG. 2

FIG. 1 is a front elevational view of a "Garment Hanger," showing my new design, the rear being a mirror image of the front shown; and

FIG. 2 is a side elevational view taken from the right of FIG. 1.

I claim:

The ornamental design for a garment hanger, substantially as shown and described.
